(57) **CLAIM**

The ornamental design for a medical stand as shown and described.

DESCRIPTION

FIG. 1 is a top front right perspective view of a medical stand showing my new design;

FIG. 2 is a bottom rear left perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof;

FIG. 8 is a bottom plan view thereof;

FIG. 9 is a top front left perspective view of the medical stand without the environment bottles; and,

FIG. 10 is a bottom rear right perspective view thereof.

The broken line showing bottles in FIGS. 1-8 is included for the purpose of illustrating environmental structure and forms no part of the claimed design.

1 Claim, 10 Drawing Sheets
